UNITED STATES PATENT OFFICE

EDWARD C. HUTH, OF MILWAUKEE, WISCONSIN, ASSIGNOR TO HUTH & JAMES SHOE MANUFACTURING COMPANY, OF MILWAUKEE, WISCONSIN, A CORPORATION OF WISCONSIN

DESIGN FOR A SHOE

Application filed April 16, 1930. Serial No. 35,266. Term of patent 3½ years.

To all whom it may concern:

Be it known that I, EDWARD C. HUTH, a citizen of the United States, residing at Milwaukee, in the county of Milwaukee and State of Wisconsin, have invented a new, original, and ornamental Design for a Shoe, of which the following is a specification, reference being had to the accompanying drawing, forming part thereof.

In the drawing Fig. 1 is a front perspective view of the right side of a shoe showing my new design; and Fig. 2 is a front perspective view of the left side of a shoe.

I claim:

The ornamental design for a shoe substantially as shown.

EDWARD C. HUTH.
